Primary Examiner — Kendra Leslie Hamilton*Assistant Examiner* — Elizabeth S Struble(57) CLAIM

The ornamental design for a belly wrap, as shown and described.

DESCRIPTION

FIG. 1 is a front perspective view of a belly wrap showing my new design;

FIG. 2 is a left-side elevation view thereof;

FIG. 3 is a right-side elevation view thereof;

FIG. 4 is a top plan view thereof;

FIG. 5 is a bottom plan view thereof;

FIG. 6 is a front elevation view thereof;

FIG. 7 is a rear elevation view thereof; and,

FIG. 8 shows a front view of the belly wrap of FIG. 1 in use condition.

The drawings are shaded to indicate the contrasting surfaces. The broken line showing on the belly wrap depicts stitching and forms no part of the claimed design.
